(57) **CLAIM**

The ornamental design for an electrical contact arrangement, as shown and described.

DESCRIPTION

FIG. 1 is a bottom, left, front perspective view of an electrical contact arrangement, showing our design;

FIG. 2 is a top, right, rear perspective view thereof;

FIG. 3 is a bottom plan view thereof;

FIG. 4 is a top plan view thereof;

FIG. 5 is a front elevation view thereof;

FIG. 6 is a rear elevation view thereof;

FIG. 7 is right plan view thereof; and,

FIG. 8 is a left plan view thereof.

The broken lines in the drawings depict portions of the electrical contact arrangement that form no part of the claimed design. The dash-dot broken lines define the bounds of the claimed design and form no part thereof.
